WITNESS:

William R. Klier.
INVENTOR
BY Victor J. Evans.
ATTORNEY

UNITED STATES PATENT OFFICE.

WILLIAM R. KLIER, OF BANTRY, NORTH DAKOTA.

MATCH-SCRATCHING ATTACHMENT FOR LANTERNS.

Application filed March 29, 1924. Serial No. 702,911.

To all whom it may concern:

Be it known that I, WILLIAM R. KLIER, a citizen of the United States, residing at Bantry in the county of McHenry and State of North Dakota, have invented new and useful Improvements in Match-Scratching Attachments for Lanterns, of which the following is a specification.

This invention relates to attachments for lanterns and has for its object the provision of a novel match scratcher adapted to be clamped on one side of a lantern frame in convenient position so as to facilitate lighting the lantern.

An important object is the provision of a device of this character which will be simple and inexpensive to manufacture, easy to mount, convenient in use, and a general improvement in the art.

With the above and other objects and advantages in view the invention consists in the details of construction to be hereinafter more fully described and claimed and illustrated in the accompanying drawings, in which:

Figure 1 is an elevation of a lantern showing my device applied and

Figure 2 is a perspective view of the attachment alone.

Referring more particularly to the drawings the letter A designates a lantern of a very common type including a frame B within which is mounted the globe C above the base D.

In carrying out my invention I provide an igniting device which is formed as a rectangular piece of metal 10 which may very conveniently be tin. At one end this metallic sheet, piece or strip is formed with elongated tongues 11 and the opposite end is formed with slots 12 through which the tongues may be inserted. It is intended that the length of this piece be such that it may go entirely around one side of the frame B.

While it is true that the member 10 might be any desired surface formation, it is preferable to stamp or press it to define pairs of transverse ribs 13 between which are other ribs 14 arranged in a V-shape to define a

relatively large rough area on which a match may be scratched and ignited.

To apply the device, it is merely wrapped about one side of the frame B with the tongues 11 inserted through the slots 12 and bent back. In actual practice the attachment will be of great benefit on account of its convenience especially as it is near the burner so that there will be little likelihood of the flame of the match being extinguished in stormy weather before lighting of the wick is accomplished.

While I have shown and described the preferred embodiment of my invention it is of course to be understood that I reserve the right to make such changes in the form, construction and arrangement of parts as will not depart from the spirit of the invention or the scope of the subjoined claims.

I claim:

1. A match scratching device formed from a single sheet of resilient metal provided at one side with elongated spaced parallel tongues and provided at its opposite sides with slots through which said tongues are adapted to be inserted and subsequently bent over, said sheet of material being formed with a plurality of transversely extending pressed out ribs arranged in pairs, and the sheet being further formed between the ribs of each pair with a series of V-shaped pressed ridges extending in angular relation to said ribs, the provision of the ribs and ridges defining an abrasive surface upon which a match may be struck by movement in any direction with respect to the sheet.

2. A match striking attachment for a support comprising a metallic sheet formed with spaced pairs of ridges and formed with groups of inclined converging ridges located between said pairs to define an abrasive surface, one end of the sheet being formed with elongated spaced tongues and the other end being formed with slots for the reception of said tongues, the sheet being adapted to be coiled about a support with the tongues engaged through said slots and bent over.

In testimony whereof I affix my signature.

WILLIAM R. KLIER.
